UNITED STATES PATENT OFFICE.

ELBERON D. SMITH, OF BROOKLYN, NEW YORK, ASSIGNOR TO AMERICAN MACHINE & FOUNDRY COMPANY, OF NEW YORK, N. Y., A CORPORATION OF NEW JERSEY.

CIGARETTE-ROD-SEALING DEVICE.

1,084,044.

Specification of Letters Patent. Patented Jan. 13, 1914.

Application filed October 21, 1912. Serial No. 726,872.

To all whom it may concern:

Be it known that I, ELBERON D. SMITH, a citizen of the United States, residing at Brooklyn, county of Kings, and State of New York, have invented a new and useful Improvement in Cigarette-Rod-Sealing Devices, of which the following is a specification.

This invention relates to a cigarette rod sealing device particularly designed for high speed cigarette machines of the continuous rod type and in which the edges of the wrapper paper are over-lapped and pasted.

It is well known in the art that in the old machines of the continuous rod type, there was more or less slip of the rod in the rod forming tube. This slip was due to various causes among which may be mentioned: imperfect feeding whereby the quantity of tobacco within the rod varied; changing atmospheric conditions which produced a variation in the condition of the tobacco within the rod due to its affinity for moisture; inaccurate adjustment of the rod forming tube itself; and to other causes not necessary to be mentioned herein.

Machines have been heretofore disclosed in which belts or equivalent devices contacting and running with the seams of cigarette rods were relied upon to seal the pasted seams, and in certain of these machines provision was made for moving the belt or device out of contact with the seam for inspection or other purposes. In none of such machines, however, was any provision made for varying the speed of the belt or device with respect to the speed of the cigarette rod.

It has been found in practice that in the high speed cigarette machines of the type in which the present invention is employed, the slip is greater than in the old relatively slow speed machines. Moreover, in high speed machines, the cigarette rod is traveling within the rod forming tube for only one-half of the time that it was in the old machines. This tends to cause the rod to open up after it leaves the tube for the reason that the paste does not have time to set while the rod is within the rod forming tube.

The main object of the present invention is the production of a device adapted for use in high speed cigarette machines and which will overcome the defect inherent in

the old machines, and properly seal the cigarette rod after it leaves the cigarette rod forming tube.

A further object is the production of a device of the general character above outlined and which includes a movable member traveling with the cigarette rod to exert pressure upon the seam of the same without setting up friction as was the case in the forming tubes of the old machines. 60

A further object is the production of a sealing device having a member traveling with the cigarette rod for sealing the same and provided with means whereby its speed may be varied in accordance with the speed 70 of the cigarette rod due to atmospheric changes or other causes.

With these and other objects not specifically mentioned in view, the invention consists in certain constructions and combinations which will be hereinafter fully described and then specifically set forth in the claims hereunto appended. 75

In the accompanying drawings which form a part of this specification and in which like characters of reference indicate the same or like parts, Figure 1 is a plan view of a device constructed in accordance with the invention; Fig. 2 is a front elevation of the device shown in Fig. 1; Fig. 3 is 80 an end elevation of the structure shown in Fig. 1, the view being taken from the right of said figure; and Figs. 4, 5 and 6 are respectively sectional views taken on the lines 4, 4, 5, 5 and 6, 6 in Fig. 1. 90

In carrying the invention into effect there is provided a cigarette rod forming mechanism adapted to move the rod longitudinally during and after its formation, a seaming or pasting device, and a sealing device including operating connections and a member traveling with the cigarette rod and exerting pressure upon the seam thereof. In the best constructions there is also provided means for varying the relative speeds of the 100 cigarette rod and sealing device. All of these mechanisms and devices may vary in construction within wide limits.

The device selected to illustrate the invention is to be understood as being one of many possible constructions within the invention. 105

Referring to the drawings, 1 indicates the bed of a cigarette machine of the high speed type. Mounted upon the bed 1 is a bracket 110

2 which serves to support a rod forming mechanism generally indicated by the character 3. The particular details of construction of this rod forming mechanism lie 5 wholly beyond the range of the present invention and is unnecessary to a full understanding thereof. A detailed description of the rod forming mechanism is therefore omitted in the interest of brevity and clearness. There is further provided what may 10 be termed a seaming device; that is to say, a device which coöperates with the rod forming mechanism to fasten the edges of the wrapping paper together to inclose the rod 15 of tobacco. This seaming device is indicated by the broken lines at 4 which show diagrammatically the paste applying wheel of a seaming or pasting device well known in the art. The particular construction of this 20 seaming device lies beyond the range of the present invention and is unnecessary to a full understanding thereof, and a detailed description and illustration thereof is therefore omitted in the interest of brevity and 25 clearness.

For the purpose of sealing the wrapping paper after paste has been applied thereto, or the wrapping paper has been otherwise seamed, there is provided a sealing device 30 including a belt 5 which over-rides the seam of the rod as it is advanced from the rod forming mechanism and under-rides a bar 6 suitably supported upon a bracket 7 screwed or otherwise fastened to the main 35 bracket 8 of the sealing device. The belt 5 over-runs pulleys 9 and 10. The pulley 10 is secured to a short shaft 11 journaled in a bearing 12 formed in the main bracket 8 before referred to. The pulley 10 is held upon 40 the shaft by means of a nut 13 which coöperates with a collar 14 at the opposite end of the shaft to prevent longitudinal displacement of the shaft 11 in a well-known manner. The pulley 9 is fast upon a shaft 15, 45 which shaft is journaled in bearings 16 and 17 formed in the bracket 8. The pulley 9 is held upon the shaft 15 by means of a nut 18 which coöperates in a well-known manner with a collar 19 pinned to the opposite end 50 of the shaft to prevent longitudinal displacement of said shaft. Overriding the upper run of the belt 5 is a tightening pulley 20. This pulley is journaled upon a stud 21 carried upon one end of a two-armed lever 55 22, 23. This lever is fulcrumed upon a stud 24 which is fixed in the boss 25 upstanding upon the bracket 8 before referred to. The arm 23 is provided with a thumb-screw 26, the lower end of which contacts with the 60 main bracket 8. It will be readily understood that manipulation of the screw 26 will result in slackening or tightening the belt as desired.

The shaft 15 is provided with a spline 27 65 upon which is mounted a slidable fric-

tionally driven wheel 28. This wheel is engaged by a fork 29 having an internally threaded boss 30. Within this boss lies a screw 31 which is journaled in bosses 32, 33 upstanding from the main bracket 8 before referred to. Longitudinal movement of the screw is prevented by means of a collar 34 and a knob 35, both of which are pinned to the screw and lie one on either side of the boss 33. The frictionally driven wheel 28 is in contact with a frictional driving wheel 36, which driving wheel is pinned to a shaft 37 extending at right angles from the shaft 15. The shaft 37 is journaled in sleeves 38 and 39 which are held by means of set screws 40 in bosses 41, 42 formed on the main bracket 8 before referred to. The shaft 37 is driven by means of a belt 43 and pulley 44, the belt 43 deriving its motion from any suitable moving part of the machine in connection with which the device is used. The sleeves 38 and 39 are journaled in hubs 45, 46 formed in the upper part of a standard 47 rising from the main bed 1 of the machine. The driving wheel 36 and the driven wheel 28 are held in contact by the action of a spring 48 surrounding the shaft 47 and interposed between the pulley 44 and a ball bearing 49 of well-known construction.

It will be readily understood that the speed of the belt may be varied by operation of the screw 31 which, through the medium of the fork 29, produces a movement of the driven wheel 28 toward or away from the axis of rotation of the driving wheel 36. It will be readily understood also that the pivotal mounting of the main bracket 8 of the device upon the sleeves 38 and 39 carried by the hubs 45 and 46 of the standard 48 provides means whereby the belt and its operating connections may be moved away from the cigarette rod to expose the same for inspection. For the purpose of limiting the pressure of the belt 5 upon the cigarette rod and for the further purpose of providing a stop limiting the return movement of the sealing device after inspection, the device is provided with a screw 50 which is threaded through a boss 51 formed on the main bracket 8 of the device. This screw is provided with a knurled head 52 and with an elongated lock nut 53. The lower end of the screw 50 contacts with a ledge 54 formed on the standard 47 before referred to. By an inspection of Fig. 6, it will be readily understood that the screw 50 operates to limit the downward movement of the main bracket 8. It is obvious that by manipulation of this screw the relative positions of the cigarette rod and of the belt 5 may be varied at will during the operation of the device to accommodate a thicker or thinner cigarette rod.

In view of the foregoing, a detailed description of the operation of the device is deemed unnecessary and is therefore omitted.

What is claimed is:

1. The combination with a cigarette rod forming mechanism, of a seaming device, a sealing mechanism including operating connections and a member traveling with the cigarette rod and exerting pressure upon the seam of the rod, and adjusting means for varying the speed of one of said mechanisms to cause the rod forming mechanism and the sealing mechanism to operate at substantially the same speed.
2. The combination with a cigarette rod forming mechanism, of a seaming device, a sealing device including operating connections and a member traveling with the cigarette rod and exerting pressure upon the seam of the rod, and means for varying the speed of the traveling member of the sealing device while the machine is in operation to cause the rod forming mechanism and the sealing device to operate at substantially the same speed.
3. The combination with a cigarette rod forming mechanism, of a seaming device, a sealing device including operating connections and a belt over-riding and traveling with the cigarette rod and exerting pressure upon the seam of the rod, and means for varying the speed of the belt while the machine is in operation to cause the rod forming mechanism and the sealing device to operate at substantially the same speed.
4. The combination with a cigarette rod forming mechanism, of a seaming device, a sealing device including operating connections and a pressure bar spaced from and overlying the cigarette rod and including a belt under-running the pressure bar and over-riding the seam of the rod, and means for varying the speed of the belt while the machine is in operation to cause the rod forming mechanism and the sealing device to operate at substantially the same speed.
5. The combination with a cigarette rod forming mechanism, of a seaming device, a sealing device including operating connections and a pressure bar spaced from and overlying the cigarette rod and including a belt under-running the pressure bar and over-riding the seam of the rod, means for varying the speed of the belt while the machine is in operation, and means for varying the relative positions of the cigarette rod and the pressure bar.
6. The combination with a cigarette rod forming mechanism, of a seaming device, and a sealing device comprising a member traveling with the cigarette rod and exerting pressure upon the seam of the rod, and a variable speed frictional driving mechanism for operating the traveling member while the machine is in operation to cause the rod forming mechanism and the sealing device to operate at substantially the same speed.
7. The combination with a cigarette rod forming mechanism, of a seaming device, and a sealing device comprising a belt traveling with the cigarette rod and exerting pressure upon the seam of the rod, and a variable speed frictional driving mechanism for operating the belt while the machine is in operation to cause the rod forming mechanism and the sealing device to operate at substantially the same speed.
8. The combination with a cigarette rod forming mechanism, of a seaming device, and a sealing device comprising a pressure bar spaced from and overlying the cigarette rod and a belt under-running the pressure bar and over-riding the seam of the rod and a variable speed frictional driving mechanism for operating the belt while the machine is in operation to cause the rod forming mechanism and the sealing device to operate at substantially the same speed.
9. The combination with a cigarette rod forming mechanism, of a seaming device, and a sealing device comprising a pressure bar spaced from and overlying the cigarette rod and a belt under-running the pressure bar and over-riding the seam of the rod and means for varying the relative positions of the cigarette rod and the pressure bar and a variable speed frictional driving mechanism for operating the belt while the machine is in operation to cause the rod forming mechanism and the sealing device to operate at substantially the same speed.
10. The combination with a cigarette rod forming mechanism, of a seaming device, and a sealing device comprising a pressure bar spaced from and overlying the cigarette rod and a belt under-running the pressure bar and over-riding the seam of the rod and means for varying the relative positions of the cigarette rod and the pressure bar and a screw controlled variable speed frictional driving mechanism for operating the driving member while the machine is in operation to cause the rod forming mechanism and the sealing device to operate at substantially the same speed.
11. The combination with a cigarette rod forming mechanism, of a seaming device, and a sealing device comprising a belt traveling with the cigarette rod and exerting pressure upon the seam of the rod and a variable speed frictional driving mechanism operative while the machine is in operation to cause the rod forming mechanism and the sealing device to operate at substantially the same speed said sealing device being movable from its operative position to expose the cigarette rod for inspection.
12. The combination with a cigarette rod forming mechanism, of a seaming device, and a sealing device comprising a belt traveling with the cigarette rod and exerting

pressure upon the seam of the rod and a variable speed frictional driving mechanism operative while the machine is in operation to cause the rod forming mechanism and the sealing device to operate at substantially the same speed and a support to which the sealing device is pivoted, said pivotal connection permitting a movement of the belt from its operative position to expose the cigarette rod for inspection.

13. In a cigarette rod sealing device, the combination with a pair of pulleys, of a belt, the operating run of the belt being adapted to travel with a seamed cigarette rod, a shaft driving one of the pulleys, a driven frictional wheel slideable upon and rotatable with said shaft, a driving frictional wheel contacting with the driven wheel, a second shaft supporting the driving wheel, means for rotating said second shaft, means for shifting the driven wheel along its shaft, and a bracket supporting the belt and driven wheel with its shaft, said bracket being

swingable about the axis of the driving wheel shaft.

14. In a cigarette rod sealing device, the combination with a pair of pulleys, of a belt, the operating run of the belt being adapted to travel with a seamed cigarette rod, a shaft driving one of the pulleys, a driven frictional wheel slideable upon and rotatable with said shaft, a driving frictional wheel contacting with the driven wheel, a second shaft supporting the driving wheel, means for rotating said second shaft, and a screw actuated fork engaging the driven wheel and adapted to shift it along its shaft.

In testimony whereof I have signed my name to this specification in the presence of two subscribing witnesses.

ELBERON D. SMITH.
